UNITED STATES PATENT OFFICE.

JACOB P. TIRRELL, OF SOMERVILLE, MASSACHUSETTS, ASSIGNOR TO THE ELECTRIC GAS LIGHTING COMPANY, OF PORTLAND, MAINE.

AUTOMATIC CIRCUIT-OPENER.

SPECIFICATION forming part of Letters Patent No. 374,017, dated November 29, 1887.

Application filed January 31, 1887. Serial No. 225,980. (No model.)

To all whom it may concern:

Be it known that I, JACOB P. TIRRELL, of Somerville, county of Middlesex, State of Massachusetts, have invented an Improvement 5 in Automatic Circuit-Openers, of which the following description, in connection with the accompanying drawings, is a specification, like letters on the drawings representing like parts.

My invention relates to an automatic circuit-opener intended to be used in circuits of the kind commonly employed for gas-lighting, which in their normal operation are only closed momentarily for the purpose of producing a spark and thus lighting the gas. In such systems, when the circuit becomes accidentally closed for a considerable period of time, through the crossing of wires or imperfect insulation, the battery is soon exhausted, 20 so that it will no longer operate.

It is customary in applying gas-lighting apparatus to buildings to group portions of the burners in different circuits, all of which branch from a single battery, and one object 25 of the present invention is to provide an instrument by which when any one of the circuits becomes closed or grounded that one circuit will be automatically opened before the battery has time to become exhausted, but all 30 the other circuits will be left in normal working condition, so that the main part of the apparatus can be used before the circuits are inspected and the imperfect one repaired. The instrument also operates as an indicator to 35 show which circuit has become deranged.

The circuit-opening instrument forming the subject of the present invention comprises an electro-magnet and normally-closed circuit-breaker in each circuit, one member of which 40 circuit-breaker is affected and moved by the magnet, which cannot, however, of itself open the circuit; and the instrument also comprises a clock-work or motor having a detent controlled by each of the magnets, so that it is released whenever any one of the magnets is 45 energized, and the said motor controls the other member of the different circuit-breakers in such manner that, if the motor remains in operation for a predetermined period of time 50 longer than that required for closing the circuit to light the gas, it will move the member

of the circuit-breaker far enough to open that particular circuit-breaker the other member of which is controlled by the magnet that is energized.

The invention also consists in various details of construction, hereinafter pointed out.

Figure 1 is a front elevation of a circuit-breaking instrument embodying this invention; Fig. 2, a vertical section thereof on line 60 *x*, Fig. 1; and Figs. 3 and 4, sectional details to be referred to.

The battery and spark-coil—such as commonly used in gas-lighting apparatus—may be connected with the metallic frame *a a'* of 65 the instrument, as indicated, by the wire 2, and thence the circuit is continued to the clock-controlled member *b* (see Fig. 2) of the various circuit-breakers, which member consists of a contact-bar, upon which rests a series of springs, *c c'*, (see Fig. 2,) connected with armature-levers *c'* of a series of electromagnets, *d*, corresponding with the number of circuits to be controlled. The armature of each magnet is connected with one terminal 70 of the same magnet, as indicated at 3, Fig. 1, and the other terminal of the said magnet is connected, as at 4, with the circuit leading to the different burners or points where the momentary current is to do its work. Thus as 75 long as the spring, *c*, corresponding to any magnet remains on the bar *b* the circuit is complete to the burner, and may be closed at the burner or at any other desired point in the usual manner, for the purpose of producing a 80 spark and lighting the gas. When the circuit is thus closed, either for lighting the gas or for any other purpose, the corresponding magnet, *d*, is energized, its armature attracted, and the spring *c* caused to move on the bar *b*, 85 but not far enough to draw its end off the bar, although the spring of any magnet which is energized will rest on the bar at a point nearer its end than the spring of the magnets which are not energized, and consequently a movement of the bar *b* toward the ends of all the springs *c* (that is, in the left-hand direction, 90 as indicated by the arrow in Fig. 2) will carry the bar out from beneath the spring the magnet of which is energized before it will carry 95 it from beneath the spring of the magnets which are not energized. The bar *b* is caused 100

to move slowly in the direction toward the ends of the springs, whenever any one of the magnets is energized, by a clock-work or motor, e , which may be of any usual construction 5 and actuated by a mainspring, e^1 , in the usual manner, the said spring driving a speed-increasing train of wheel-work terminating in a governor, (shown as a fan, e^2 ,) by which the speed of movement of the said train is regulated. The operation of the said motor is controlled by a detent, e^3 , connected with a lever, e^4 , (see Fig. 3,) fixed on a shaft, e^5 , connected with a bar, e^6 , that extends along in contact with the armature-levers e^7 of the lower magnets, d , (see Fig. 1,) the said bar e^6 being composed of insulating material, so as not to connect electrically with the said armatures.

In order to economize space, the magnets d are arranged part above and part below the 20 member b of the circuit-breakers, which is thus arranged to co-operate with the springs c above and c' below, and the armatures of the upper magnets co-operate with a bar, e^{60} , on a shaft, e^{50} , provided with a lever, 25 e^{40} , (see Fig. 3,) that is forked at its end and engaged with a pin, f , entering a corresponding fork or notch in the end of the lever e^4 , so that a movement of the bar e^{60} produced by the armature of any one of the upper magnets 30 has the same effect on the detent e^3 as the movement of the bar e^6 produced by one of the lower magnets—that is, it disengages said detent and releases the motor.

One of the slow-moving shafts, g , of the motor 35 has an extension, g' , connected to rotate with the said shaft g , but with a sufficiently loose connection to permit a slight angular movement of the part g' with relation to the part g . The said part g' is provided with a toothed 40 wheel, h , (see Fig. 3,) and the end of the shaft g' has its bearing in a slide-bar, h' , that carries the pin f , that enters the notch in the ends of the levers e^4 and e^{40} . The other end of the bar h' is forked and engages a shaft, i , that extends 45 along the back of the circuit-breaker bar b , as shown in Fig. 2.

The movement of the pin f , produced by either of the levers e^4 e^{40} when the corresponding bars, e^6 or e^{60} , are moved by the 50 armature of any one of the magnets d , moves the toothed wheel h toward and into engagement with a toothed segment, i' , on the shaft i , so that when any one of the magnets is energized it causes the motor to be released and the wheel h , actuated by the said motor, to engage the segment i' , and thus rotate the shaft i as long as the magnet remains energized.

The bar b , forming one member of the circuit-breakers, is connected at its ends with 60 end pieces, b' , (see Figs. 2 and 4, the latter being a partial plan view of this part,) and is connected also by a rod, b^2 , the whole forming a rigid frame which is capable of having a sliding movement in the stationary 65 frame-pieces a a' , the end pieces, b' , being notched where they engage the shaft i , as seen in Fig. 2, and the said frame is pressed toward

the rearward—that is, toward the left hand in Fig. 2—by a spring, b^3 .

The bar b rests against cams or eccentrics i^2 70 on the shaft i , which is normally held with the greatest throw of the eccentrics toward the bar b , as shown in Fig. 2, being at once moved to this position by the action of a spring, i^4 , on the segment i' whenever the latter is disengaged from the wheel h , which is the normal condition. When, however, the wheel h and segment i' are engaged and the shaft i rotated, the movement of the eccentrics i^2 , one near either end of the said shaft, will permit the 80 frame b b' b^2 to be moved backward by the spring b^3 , and at the end of a predetermined period of time—usually about half a minute—it will have moved far enough to carry the bar b beyond the end of the particular spring, 85 c or c' , the magnet of which is then energized, permitting the said spring to drop, as shown at c^{10} , Fig. 2. The dropping of the spring will at once break the circuit between it and the bar b of the magnet that has been energized for the abnormal period of time, and the said armature returning to its normal position will cause or permit the detent to stop the motor, and will also cause the disengagement of the wheel h and segment i' , so that the latter will be immediately restored by the spring 90 i^4 to its normal position, thus causing the frame b b' b^2 to return to its normal position, so that it will require the same period of time to again elapse after any one of the magnets 95 is energized before the circuit of the said magnet will be broken. The shaft i and connected devices thus constitute a spring-actuated controlling device for governing the position of the circuit-breaker member b , the said device 100 being actuated against the force of the spring by the motor. The movement of the frame can never be sufficient to disengage the bar b from the spring, c or c' , of any magnet which is not energized while the said movement is 105 taking place, so that none of the circuits will be affected except the one that has been closed for an abnormal period of time.

A plate, p , pivoted on a shaft, p' , operating in the end pieces, b' , and having a handle, p^2 , 115 can be used to restore the spring c^{10} , that has operated to break the circuit, into its normal position, resting on the end of the bar b , the said plate being normally held by a spring, p^3 , in an intermediate position between the 120 springs c and c' , so that they will not come in contact with the said plate when they drop.

It will be seen that the dropping of any one of the springs indicates which circuit is de-ranged.

I claim—

1. The combination of a number of magnets in different branch circuits and a circuit-breaker in each of said circuits, one member of which circuit-breaker is controlled by the 130 armature of the magnet in the same circuit, and the other member of which circuit-breakers is common to all the said circuits, being connected with the main circuit, of which they

are branches, and a motor the operation of which is controlled by each of the said magnets, which motor moves the member common to all the circuit-breakers and at the end of 5 a predetermined period of time breaks the circuit containing any magnet that remains energized during the said period of time, substantially as described.

2. The combination of a movable conducting strip or bar, and motor for moving the same, with a series of electro-magnets and contact-springs connected with the armatures thereof, normally resting on said bar near their ends, the movement of said springs produced by the 10 attraction of the magnet bringing the ends of the springs nearer the bar, but being insufficient to move the springs off the bar, combined with a motor for moving said bar toward the ends of the springs and a detent for said motor, by which the latter is released and remains in operation as long as any one of said magnets is energized, substantially as described.

3. The combination of a conducting-bar and number of magnets and armatures therefor 25 and the contact-springs carried by said armatures resting on said bar, a spring-actuated device controlling the position of the said bar, and the motor normally disengaged from said device, and a detent for said motor, and mechanism actuated by the armatures of the said 30 magnets, whereby the motor is released and engaged with the bar-actuating device during

the time that one of the said magnets remains energized, substantially as described.

4. The combination of the conducting-bar 35 and two sets of contact-springs resting on opposite edges thereof with a motor for moving said bar and two sets of electro-magnets co-operating with said springs, and each controlling the operation of the said motor, and a restoring device located between the two sets of springs for replacing a contact-spring of either set on the said bar after it has been disengaged therefrom by the movement of the bar, substantially as described.

5. The combination of a series of contact-springs and a conducting-bar co-operating therewith, and a shaft controlling the position of the said bar, with a motor having an actuating-wheel normally disengaged from said 50 controlling-shaft, a detent for said motor, and a series of electro-magnets and armatures therefor co-operating with the said contact-springs, and each controlling the said detent and the engagement of the motor with the controlling-shaft, substantially as described.

In testimony whereof I have signed my name to this specification in the presence of two subscribing witnesses.
